CLAIM

The ornamental design for a mesh seat, as shown and described.

DESCRIPTION

FIG. 1 is a top perspective view the present invention; FIG. 2 is a front view of the present invention;

FIG. 3 is a left side view of the present invention;

FIG. 4 is a back view of the present invention;

FIG. 5 is a top view of the present invention;

FIG. 6 is a bottom view of the present invention; and,

FIG. 7 is a right side view of the invention.

The broken lines, where present, illustrate portions of the mesh seat that form no part of the claimed invention.
